UNITED STATES PATENT OFFICE.

HARRY SPIRO AND EARL WILLSON WELLS, OF SAN FRANCISCO, CALIFORNIA, AS-
SIGNORS OF ONE-HALF TO ALEXANDER LEVISON, OF SAN FRANCISCO, CALIFORNIA.

FLUOROSCOPIC STAND.

Application filed November 14, 1922. Serial No. 600,812.

This invention relates to an X-ray apparatus, and particularly pertains to a fluoroscopic stand.

In making X-ray examinations of the internal organs, it has been found essential to proper exploration and diagnosis that the subject be turned at different angles to the observer so that the exact condition of the parts under observation can be more readily observed. At the present time it is common practice to require the patient to move from one angle of vision to another, and this has led to confusion and inaccuracy, it being the object of the present invention to provide means for fixing the patient relative to the X-ray tube and the screen and to insure that the angular position of the patient may be accurately determined for immediate observation or for repeated observation at different times.

The present invention contemplates the use of a revoluble back rest, which back rest may be turned to a desired angle and set, the angle being easily read in the dark by an illuminated member carried by the platform.

The present invention is illustrated by way of example in the accompanying drawings, in which:

Fig. 1 is a view in side elevation showing the invention used while in an upright position.

Fig. 2 is a view in plan, particularly showing the base of the device and the indicating means carried thereby.

Fig. 3 is a view in side elevation showing the device when disposed horizontally.

Fig. 4 is a view in perspective showing another form of the present invention.

Referring more particularly to the drawings, 10 indicates a base. This member is here shown as rectangular in section and as having graduations 11 formed upon its upper face. These graduations are arranged concentrically around a pivot pin 12, upon which pin a platform 13 is pivotally mounted. The platform is adapted to rotate around the pin and to rest upon bearing casters 14 which travel along a channel 50 trackway 15.

Secured to the rear edge of the platform 13 and extending at right angles thereto is a back rest 16. This rest is preferably concaved so that it will serve as a comfortable support for the back of a patient, while

either in a horizontal or vertical position. Diagonal braces 17 serve to reinforce the back rest and to more rigidly secure it in relation to the platform. A pointer finger 18 is secured centrally of the forward edge 60 of the platform 13 and is adapted to register with the various graduations 11.

A recess 18' is formed in the edge of the platform adjacent the mounting of the pointer to receive a box 19 carrying a lamp 65 socket 20 and incandescent lamp 21. The outer face of this box is preferably closed by a glass 22, through which the rays of light from the box may fall on the dial 70 graduations.

In some instances it may be desirable to dispose the patient in a horizontal position while making an observation, and with that purpose in view an auxiliary support 23 has been provided. This support is secured to 75 a pivot casting 24 by a removable pin 25. The casting 24 is fixed to the upper end of the back rest 16 and has a bearing at its outer end which is in longitudinal alignment with the pivot 12 of the base. It will 80 thus be evident that by turning the stand down as shown in Fig. 3 it will be swung from the pivot pin 25 and the pin 12 while utilizing the base 10 and the auxiliary member 23 as supports. The back rest and platform may be locked in any desired position by means of a pin 26 which is secured to the edge of the platform within a bearing 27. This pin is spring pressed against the upper face of the base 10 and may be lifted 85 to permit the platform to turn, after which the spring will again hold the pin against the base in a manner to prevent turning of the platform.

Reference being had to Fig. 4 of the 95 drawing, it will be seen that instead of revolving the platform upon which the patient stands, the platform is made stationary and the back rest 29 revolves. This rest is provided with straps 30 by 100 which it may be positioned against the body of the patient. The rest is supported by a rod 31 and may be adjustably held relative thereto by a bearing 32 and a set screw 33. The upper end of the rod 31 is pivoted for 105 horizontal rotation from a plate 34. This plate carries a dial 35 similar to that shown in Fig. 2 of the drawing. A pointer 36 is carried by the rod and moves over the 110 face of the dial so that the position of the

patient may be accurately determined in the same manner and for the same purpose as previously described.

In operation of the present invention it will be assumed that the patient is disposed in a vertical position, as might be the case when heart observations are taken. By causing the patient to stand squarely on the platform and lean against the back rest it will be possible for this position to be held for a considerable time without fatigue. The observations may then be taken at any desired angle by merely swinging the stand upon its pivot 12 and locking the stand by releasing the lock pin 26. The angle would be determined by registration of the fingers 18 with the graduations of the dial. It will also be observed that one of these fingers is secured in the rear of the back rest, thus making it possible to completely reverse the patient and to still accurately set the platform.

When it is desired to place the patient in a horizontal position, as when intestinal observations are to be made, the stand may be turned with the back rest horizontal, after which the support 23 is secured to the member 24 by the pin 25.

It will thus be seen that the device here disclosed provides a simple and convenient means for rapidly and accurately disposing a subject in a desired position relative to an X-ray apparatus.

While we have shown the preferred form of our invention, as now known to us, it will be understood that various changes might be made in the combination, construction and arrangement of parts by those skilled in the art, without departing from the spirit of the invention as claimed.

Having thus described our invention, what we claim and desire to secure by Letters Patent is:

1. A fluoroscopic stand comprising a platform, a base member upon which it is revolvably mounted, a back rest carried by the platform, a bearing secured at the opposite end of the back rest from the platform and an auxiliary supporting device adapted to be pivotally secured to the bearing and to cooperate with the base in pivotally supporting the back rest in a horizontal position.

2. A fluoroscopic stand comprising a platform, a base member upon which it is revolvably mounted, a back rest carried by the platform, a bearing secured at the opposite end of the back rest from the platform, an auxiliary supporting device adapted to be pivotally secured to the bearing and to cooperate with the base in pivotally supporting the back rest in a horizontal position, and means for securing the platform at a desired angle to the base.

HARRY SPIRO.

EARL WILLSON WELLS.
